LIGHTING FIXTURE

Samuel S. Dauman, New York, N. Y.

Application February 14, 1934, Serial No. 711,086

1 Claim. (Cl. 240—78)

The present invention relates broadly to the art of illumination and more especially to a lighting fixture unit adapted for indoor illumination with the major portion of the light thrown downwardly.

The present invention comprises an improvement upon my United States Patent No. 1,939,956, patented December 19, 1933.

More especially the present invention comprises a lighting fixture constructed to deliver the majority of the light downward and at the same time reflect a sufficient amount of the light upward to illuminate the ceiling. The intense light from the fixture is delivered downwardly in the form of a cone while a sufficient amount of light is reflected upwardly to obviate heavy shadows above the fixture.

In the preferred form, the device comprises a supporting member for an electric incandescent light and wherein the incandescent light is enclosed within a reflecting dome preferably of metal and preferably having an aluminum satin or sand blasted surface. This reflecting member is adapted to carry a diffusion translucent or transparent globe through which the reflected light and also the direct light from the incandescent lamp may pass. The globe is provided with a bead or shoulder or other positioning device to support and position a ring-like reflector to throw a portion of the light upwardly. This reflector is supported on the diffusion globe part way down on the globe so as to provide an annular zone through which light rays may pass to strike the inner surface of the reflector and be directed upwardly. This reflector preferably comprises a metallic ring and may be provided with a curved surface of such form as to diffuse the light striking the surface, whereby this annular ring reflects the light upwardly over a large area.

The fixture is of such construction as to substantially enclose the electric light in a dust-proof chamber and any dust that may collect between the ring reflector and the globe may be easily removed by simply lifting the reflector ring from its seat on the globe and cleaning the exterior of the globe.

Fig. 1 illustrates a cross-section through a preferred form of the invention.

Fig. 2 shows an elevational view of the device shown in section in Fig. 1.

The device comprises primarily a supporting member 1 which carries a dome-like reflector 2. This reflector may comprise a single piece of material as is shown in my Patent No. 1,939,956 or may be supported by a small cup-like member 4 as I have specifically illustrated herewith. This reflector preferably is provided with an inner surface of satin finish or sand blasted aluminum so

as to produce a brilliant reflector with a soft diffusion effect. An electric light socket 5 is supported within the upper portion of the dome member and carries an electric lamp 6. This lamp is fed by suitable circuit connections such as the electric wires 7.

The lower edge of the dome reflector 2 is provided with a flange 11 adapted to carry clamp screws 12 which engage an inturned rim 14 on a diffusion globe 15. This diffusion globe 15 is preferably provided with a bead or shoulder 16 upon which an annular ring reflector 17 is adapted to be seated. This ring reflector, in its preferred form, comprises a metallic member having an inner surface 18 of sand blasted or satin aluminum finish so as to provide a brilliant reflector for all light striking the reflector ring. This ring sets loosely on the bead 16 so that the matter of expansion and contraction due to the heat of the lamp or otherwise does not seriously affect the relation of the parts. This reflector preferably is provided with a wire edge or rolled rim 19 in order to stiffen the edge of the same and preferably the reflector is of a double curvature, so that the light rays striking the reflector surface 18 are reflected over a relatively large area. The main effect of the fixture is to direct a cone of intense light rays downwardly and to direct a very diffused light in an upward direction.

The present invention may be used for most indoor lighting and is particularly effective for store lighting, wherein a soft glow is provided at the ceiling with the majority of the intense light directed downwardly upon the goods on counters.

What I claim is:

A lighting fixture comprising in combination a suspension member, a reflecting dome supported by said suspension member, a receptacle for an electric light mounted within said reflecting dome and adapted to support an electric light within said dome, a translucent diffusion globe carried by said reflecting dome, said globe having an outwardly flared portion extending away from the lower edge of said dome, a supporting ledge on said diffusion globe and adjacent the lower extremity of said outwardly flared portion, said supporting ledge being spaced from said reflecting dome to provide an annular zone between said dome and said supporting ledge on said diffusion globe for transmission of light rays, and an annular ring reflecting member extending outwardly and upwardly from said diffusion globe and resting on said supporting ledge, and adapted to reflect in an upward direction, light rays transmitted through said annular zone of the diffusion globe, said ledge comprising the sole support for said reflector.

SAMUEL S. DAUMAN.
